UNITED STATES PATENT OFFICE.

EDWARD H. DEWSON, OF NEW YORK, N. Y., ASSIGNOR TO THE WESTINGHOUSE AIR BRAKE COMPANY, OF WILMERDING, PENNSYLVANIA, A CORPORATION OF PENNSYLVANIA.

SANDING DEVICE.

1,131,217.

Specification of Letters Patent.

Patented Mar. 9, 1915.

Application filed June 15, 1912. Serial No. 703,817.

To all whom it may concern:

Be it known that I, EDWARD H. DEWSON, a citizen of the United States, residing at New York, in the county of New York and 5 State of New York, have invented new and useful Improvements in Sanding Devices, of which the following is a specification.

This invention relates to sanding devices for railway service, and more particularly 10 to a valve mechanism for controlling the fluid under pressure employed in supplying sand to the rails.

The principal object of my invention is to provide an improved valve mechanism of 15 the above character.

In the accompanying drawing, Figure 1 is an elevation of an engineer's brake valve embodying my invention; Fig. 2 a horizontal section on the line *a—a* of Fig. 1, and 20 Fig. 3 a plan view of the construction shown in Fig. 1.

While my improvement may be applied to various forms of manually controlled valve mechanisms, the invention is shown 25 in the drawing in connection with a brake valve of the usual construction.

In accordance with my invention, a sand valve casing 1 is provided which is adapted to be secured to the flat horizontal face 2 30 of the brake valve 3, preferably by means of the usual brake valve bolts 4. Within the casing on opposite sides of the brake valve stem 5 are mounted valves 6 and 7. A passage 8 in the casing 1 communicates 35 with chambers 9 and 10 on one side of the valves 6 and 7 respectively and chambers 11 and 12 at the opposite side of valves 6 and 7 are in open communication with the respective passages 13 and 14 leading to a 40 sand valve port. A port 15 opens into the passage 8 and is adapted to supply fluid under pressure to said passage from a suitable source of fluid pressure such as the main reservoir. The valves 6 and 7 are 45 provided with stems 16 and 17 respectively and said stems carry push rods 18 and 19 adapted to project out from the casing, as shown. The brake valve handle 20 is provided with a downwardly extending lug 21 50 so positioned that the movement of the handle in one direction causes the lug to engage one of the push rods while the movement in the opposite direction causes the lug to engage the other push rod. The push

rod 19 is so positioned that the same is 55 adapted to be operated by the movement of the handle 20 to emergency application position, and the push rod 18 is adapted to be operated when the brake valve handle is moved slightly beyond the usual release position. 60

In operation, upon movement of the brake valve handle to emergency application position, the push rod 19 is moved inwardly 65 by the lug 21 and the valve 7 is thereby opened to admit fluid under pressure to the sand port 14. With this construction, it will also be seen, that sand can be used in starting, by moving the brake valve handle to the left of the normal release position, 70 so as to open the valve 6 for admitting fluid to the sand port. The valves 6 and 7 are normally held to their seats by the respective springs 22 and 23 and preferably the push rods 18 and 19 are constructed so as 75 to seat, when operated by the movement of the brake valve handle, and thereby prevent possible leakage of fluid under pressure around the stems of the valves.

Having now described my invention, 80 what I claim as new and desire to secure by Letters Patent, is:—

1. In a track sanding device, the combination with a brake valve device comprising valve means and an operating handle 85 therefor movable only in a direction to operate said valve means, of a valve for controlling the track sanding and a lug carried by said handle and adapted to operate the sand valve upon movement of the brake 90 valve handle beyond release position.

2. In a track sanding device, the combination with a brake valve device comprising valve means and an operating handle therefor movable only in a direction to operate 95 said valve means, of a valve for controlling the track sanding and a fixed lug on said brake valve handle for operating said sand valve both in applying and in releasing the brakes.

3. In a track sanding apparatus, the combination with a brake valve provided with an operating handle, of two valves for supplying fluid for track sanding, and means carried by the brake valve handle for operating one valve with the brakes released and for operating the other valve upon effecting an application of the brakes. 100 105

4. In a track sanding apparatus, the combination with a brake valve provided with the usual operating handle and having a release position and an emergency application position, of a valve operated by movement of the brake valve handle beyond release position for supplying fluid for track sanding and a valve operated upon movement of the handle to emergency ap-

plication position for also supplying fluid 10 for track sanding.

In testimony whereof I have hereunto set my hand.

EDWARD H. DEWSON.
